UNITED STATES PATENT OFFICE.

FRANK J. HERRICK, OF NEW BRITAIN, CONNECTICUT, ASSIGNOR TO THE NORTH & JUDD MANUFACTURING COMPANY, OF SAME PLACE.

HORSEMAN'S SPUR.

SPECIFICATION forming part of Letters Patent No. 356,039, dated January 11, 1887.

Application filed October 1, 1886. Serial No. 215,040. (No model.)

To all whom it may concern:

Be it known that I, FRANK J. HERRICK, of New Britain, in the county of Hartford and State of Connecticut, have invented a certain new and useful Improvement Pertaining to Horsemen's Spurs, of which the following is a description, reference being had to the accompanying drawings, where—

Figure 1 is a side view of a spur embodying 10 said improvement attached to a boot. Fig. 2 is a view of the same from underneath.

The heel-band of the common riding-spur embraces the rear part of the rider's boot just above the boot-counter. It is generally 15 attached to the boot by a fastening-strap, which runs under the boot just forward of the heel, thence passes through the forward ends of the heel-band, and is buckled around the instep. As a result of this construction, the rear part 20 of the heel-band is left free to play up and down, thereby chafing and wearing out the boot, and also the lower end of the wearer's pantaloons. Moreover, the spur proper is liable to get into such a position by being 25 canted too far upward that it will not strike the horse fairly when the rider attempts to use the spur. The improvement in spurs which forms the subject-matter of these Letters Patent is intended to cure these and other defects app- 30 pertenant to the common form of spur.

In the accompanying drawings, the letter *a* denotes the heel-band.

b denotes the spur-stud.

The letters *c* denote trunnions projecting 35 inwardly from the forward ends of the heel-band, and taking under the sole of the boot, just in front of the boot-heel *d*, and, so far as this trunnion-like action is concerned, it is entirely feasible to extend the trunnions until 40 they meet and join in a continuous cross-bar.

The letters *e* denote points attached to the trunnions and taking into the front of the boot-heel. Obviously, they might be turned upward instead of backward and take into

the sole of the boot; but I prefer the rear- 4. wardly-projecting points. The inner side of the heel-band *a* rests either against the boot-heel or the counter of the boot, instead of being substantially above the counter, as in the old-fashioned form of spur. 5.

The letters *f* denote buttons (or equivalent devices) for attaching the fastening strap to the heel-band. These buttons are located centrally of the heel-band, by which is meant that they are located away from the front ends of 5. the heel-band at least one-quarter of the distance from the front ends to the spur-stud, and this central location of the buttons is for the purpose of making the upward and forward pull of the fastening-strap bear alike, or nearly 6. alike, at both the rear and front of the heel-band.

The letters *g* denote the fastening-strap, which buckles over the instep.

The effect of this construction of the spur, 6 just described, is to make it retain substantially one position all the time, that position being one just below the pantaloons of the wearer, and one in which the spur-stud will always be where it will act effectively when 7 the rider desires to use it in pricking his horse.

I claim as my improvement—

1. The heel-band *a*, having trunnions *c* bearing rearwardly projecting points *e*, in combination with spur-stud *b* and fastening-strap *g*, all substantially as described, and for the purpose set forth.

2. In combination, the spur-stud *b*, heel-band *a*, provided with trunnions *c*, button *f*, 8 located centrally of the heel-band, and the fastening-strap *g*, all substantially as described, and for the purpose set forth.

FRANK J. HERRICK.
